REFINING OF OILS

Robert P. Ferguson, Cranford, N. J., assignor to
Standard Oil Development Company, a corpora-
tion of Delaware

Application April 1, 1941, Serial No. 386,318

4 Claims. (Cl. 196—38)

The present invention is concerned with the refining of oils. The invention is more particularly directed to an improved combination of refining stages by which it is possible to produce higher quality petroleum oil products. In accordance with the present invention, acid treated petroleum oils are initially contacted with clay or a similar refining agent to effect decolorization of the same. The oil-clay slurry after the desired decolorization is effected is contacted with an alkaline material in order to effect the desired neutralization of the product.

It is well known in the art to treat mineral oils, particularly petroleum oils, with various acids, clays, and neutralizing reagents. For example, in the manufacture of high quality petroleum products boiling in the lubricating oil boiling range, the usual process is to remove undesirable constituents from the oil by treating with a sulfuric or an equivalent acid. The oil after separation of the acid sludge termed "acid oil" is handled in a manner to neutralize the acidic constituents, which is usually accomplished by contacting the acid oil with a suitable alkaline reagent or clay. In an operation in which an acid oil is contacted with an alkaline reagent, it is usually necessary to water wash the neutralized oil in order to remove excess caustic and entrained soaps. It is necessary that this washing process be carried out at relatively high temperatures in the range from 150° F. to 250° F., with the result that the finished oil is dark in color. Furthermore, acid oils finished by alkaline treatment generally do not have satisfactory color stabilities such as are encountered in their subsequent utilization. On the other hand, clay treatment of acid oils is satisfactory for improving the color but does not completely remove acidic bodies. This results in the treated oil having relatively low color stability. It has, therefore, been the practice to process the oil utilizing an alkaline reagent and clay. It is very desirable to carry out these separate refining operations simultaneously and to remove the clay and lime or equivalent treating agents in one filtering step. Heretofore this has not been desirable since a relatively large amount of clay was necessary in order to secure the desired decolorization. The respective reagents in the presence of each other seem to impair the efficiency of the other appreciably.

I have now discovered a process by which a marked unexpected improvement in the efficiency of the clay and the alkaline reagent is secured in which process these respective reagents are

employed in conjunction with one another. In accordance with my process, the clay or similar reagent is added to the oil, the slurry heated to the decolorizing temperature and held at this temperature for a time interval at the expiration of which the alkaline reagent is added.

The process of my invention may be readily understood by reference to the drawing illustrating an embodiment of the same. For the purpose of description, it is assumed that the petroleum oil boils in the lubricating oil boiling range. The feed oil is introduced into acid contacting zone 1 by means of feed line 2. The feed oil in zone 1 is contacted with sulfuric acid or an equivalent acid which is introduced by means of line 3 and withdrawn by means of line 4. The acid treated oil is withdrawn from zone 1 by means of line 5 and passed to mixing zone 6 wherein it is mixed with the desired amount of clay or an equivalent agent which is introduced by means of line 7. The oil-clay slurry is removed from mixing zone 6 by means of line 8, passed through heating zone 9 wherein the temperature is raised to the desired degree, which is generally in the range from about 350° F. to 600° F., and then passed into primary contacting zone 10 by means of line 11. The heated slurry is held at the desired temperature in contacting zone 10 for the desired time period after which it is withdrawn by means of line 12 and mixed with an alkaline reagent which is introduced by means of line 13. The mixture is passed through mixing zone 14 and then introduced into secondary contacting zone 16 by means of line 15. At the end of the optimum time period the oil-clay and alkaline reagent slurry are withdrawn from secondary contacting zone 16 by means of line 17, passed through cooling zone 18, and introduced into separation zone 19 which, for the purpose of description, is taken to be a filtering zone. The spent clay and spent alkaline treating agent are withdrawn from separation zone 19 by means of line 20, while the treated product is removed by means of line 21 and further treated or refined in any manner desirable.

The process of the present invention may widely vary. The invention is applicable in the treatment of any petroleum oil although it is particularly useful in the treatment of petroleum oils boiling in the lubricating oil range. Any suitable acid treating condition may be employed and the acid sludge separated from the oil in any desirable manner. In general, from about 5 to 30 pounds of 98%, or equivalent, sulfuric acid is employed per barrel of oil being treated.

The present operation may be employed when utilizing conventional decolorization clays. It is, however, particularly effective when acid treated clays such as those sold under the trade name of "Super Filtrol" are employed. The quantity of clay utilized will depend upon the character of the feed oil and the concentration of the color bodies in the oil. However, the amount of clay used is below about 1 pound of clay per gallon of oil, generally from about 0.1 to 0.7 pound per gallon of oil.

The temperature, likewise, may be adjusted depending upon the particular clay employed and the character of the oil being treated. However, in general it is preferred to contact the oil and clay at a temperature in the range from about 300° F. to 600° F., preferably at a temperature in the range from about 400° F. to 550° F. In general the treating temperature is from about 25° F. to 50° F. below the flash point of the oil being treated. The time of contacting between the oil and clay at the elevated temperature before adding the alkaline reagent likewise may vary considerably depending upon general operating conditions. It is preferred that the oil and clay be held at the elevated temperature for a time period of from 2 to 30 minutes, preferably for a time period of from 5 to 10 minutes before adding the alkaline reagent.

The amount of alkaline reagent added likewise will vary and be a function of general operating conditions. The quantity employed will vary in the general range from 0.05 to 1.0 pound of alkaline reagent per gallon of oil. It is preferred to use from 0.05 to 0.25 or 0.5 pound of alkaline reagent per gallon of oil. After the addition of the alkaline reagent it is desirable that the entire mixture be held at the elevated temperature for a time period in the range from about 2 to 5 minutes before cooling the oil and removing the clay and alkaline reagent. Any suitable alkaline reagent may be employed. However, the preferred alkaline reagents comprise alkali and alkaline earth metal hydroxides. A particularly desirable alkaline reagent comprises soda lime, consisting of about 40% to 60% of sodium hydroxide and from about 40% to 60% of calcium hydroxide.

In order to illustrate the invention further, the following examples are given which should not be construed as limiting the same in any manner whatsoever:

Example 1

A petroleum oil boiling in the lubricating oil boiling range secured as a raffinate in a solvent treating operation and having a gravity of 32° A. P. I. was treated at a temperature of 425° F. with clay and soda lime in several operations with the results as follows:

Operation	Clay per gallon oil	Soda-lime per gallon oil	Resulting Robinson color of product
1.	0.5#	None	9.0
2.	0.5#	0.25 introduced with clay	3.8
3.	0.5#	0.25 introduced after reaching 425° F.	9.0

It is to be noted that in operation 1, in which lubricating oil was contacted utilizing only clay, the resulting product had a Robinson color of 9.0. However, in operation 2, in which the clay and soda lime were utilized simultaneously, the decolorizing efficiency of the clay was materially im-

paired. In operation 3, wherein the oil was contacted with clay followed by the addition of soda lime, the decolorizing efficiency of the clay was not affected.

Example 2

A petroleum oil boiling in the lubricating oil boiling range was treated with 20 pounds of 98% sulfuric acid per 100 gallons of oil. The oil after removal of the acid sludge was clay contacted at 425° F. employing a number of operations. The results attained in these operations are as follows:

Operation	Conditions	Clay #/gallon	Soda-lime #/gallon	Color tag Robinson	Color hold tag Robinson 16 hr. at 210° F.	Neut. No. mg. KOH/gm.
20	Clay added	1/4		6.8	2.0	0.11
2.	Clay and soda-lime added simultaneously	1/4	1/16	4.0	3.8	0.5
3.	Clay added then soda-lime after 5 min. at contact temperature	1/4	1/16	6.8	5.3	0.05

Example 3

In other operations a heavy residual stock segregated from an acid treating operation utilizing 80 pounds 98% sulfuric acid per 100 gallons of oil was treated at 525° F. with the following results:

Operation	Conditions	Clay #/gallon	Soda-lime #/gallon	Color tag Robinson	Color hold tag Robinson 16 hr. at 210° F.	Neut. No. mg. KOH/gm.
40	Clay added	1/4		0.3	2.6	0.30
2.	Clay and soda-lime added simultaneously	1/4	3/8	0.2	1.7	0.08
3.	Clay added then soda-lime after 5 min. at contact temperature	1/4	3/8	0.3	2.6	0.11

Example 4

Respective portions of a petroleum oil boiling in the lubricating oil boiling range and having a viscosity Saybolt of 139 at 100° F. were treated by the following operations:

Operation	Conditions	Clay #/gallon	Soda-lime #/gallon	Color tag Robinson	Color hold tag Robinson 16 hr. at 210° F.	Neut. No. mg. KOH/gm.
60	Original oil					2.5
65	Acid treated 30 pounds of 98% acid per 100 gallons of oil	1/4		Black	3.5	1.85
1.	Clay at 300° F.	1/4		17		
2.	Caustic treated 40° Baume, then water washed			10.7	6.7	0.78
3.	Treated 40° Baume caustic, then clay	1/4	1/4	10.7	5.5	1.40
70	Clay, then caustic	1/4	1/4	16.8	11.1	0.38

Example 5

Respective portions of a petroleum oil boiling in the lubricating oil boiling range and having

a viscosity Saybolt of 675 at 100° F. were treated by the following operations:

Operation	Conditions	Clay #/gallon	Soda- lime #/gallon	Color tag Robin- son	Color- hold tag Robin- son 16 hr. at 210° F.	Neut. No. mg. KOH/ gm.
1.	Original oil Acid treated 40 pounds of 98% acid per 100 gallons of oil					2.04
2.	Clay at 380° F.	1/4		Black 15.4	8.0	1.14
3.	Caustic treated 40° Baumé, then water			11.8	9.3	0.26
4.	Caustic treated 40° Baumé, then clay	1/4		11.3	9.4	1.26
5.	Clay, then caustic	1/4	1/4	12.5	10.0	0.18

Example 6

Respective portions of a petroleum oil boiling in the lubricating oil boiling range and having a viscosity Saybolt of 1687 at 100° F. were treated by the following operations:

Operation	Conditions	Clay #/gallon	Soda- lime #/gallon	Color tag Robin- son	Color- hold tag Robin- son 16 hr. at 210° F.	Neut. No. mg. KOH/ gm.
1.	Original oil Acid treated 40 pounds of 98% acid per 100 gallons of oil					1.46
2.	Clay at 400° F.	1/4		Black 10.4	2.2	0.88
3.	Caustic treated 40° Baumé, then water			12.0	10.5	0.80
4.	Caustic treated 40° Baumé, then clay	1/4		9.7	6.4	0.69
5.	Clay, then caustic	1/4	1/4	12.8	10.7	0.05

From the above it is apparent that treatment of an acid oil with clay alone materially im-

proves the color but does not give an oil of low neutralization value or of stable color. Treatment with an alkaline reagent alone produces an oil of low neutralization value but poor color and color stability. By suitable combination of these procedures in a specific manner as disclosed by my invention, oils of low neutralization value, good color and good color stability may be obtained.

What I claim as new and wish to protect by Letters Patent is:

1. Process for the refining of petroleum oil which comprises treating said petroleum oil with a mineral acid to remove objectionable compounds therefrom, separating the acid treated oil, and heating the same in the presence of a color adsorbent to a temperature in the range from about 350° F. to about 650° F., holding the oil-clay mixture at this temperature for a time period in the range from about 5 to about 30 minutes, then adding an alkaline reagent, cooling the mixture and separating the color adsorbent and alkaline reagent therefrom.

2. Process as defined by claim 1, in which said color adsorbent is an acid treated clay, and said alkaline reagent is soda lime.

3. Process for the refining of petroleum oils boiling in the lubricating oil boiling range, which comprises contacting said oil with sulfuric acid, separating the treated oil from the acid sludge and adding clay thereto, heating the oil-clay slurry to a temperature in the range from about 350° F. to 650° F., and holding the slurry at said temperature for a time interval of about 5 to 10 minutes, then adding an alkaline reagent and holding the mixture at said elevated temperature for a time period of from about 2 to 5 minutes, cooling the mixture and separating the alkaline reagent and clay therefrom.

4. Process as defined by claim 3, in which said oil slurry is heated to a temperature in the range from about 450° F. to 550° F., said clay is an acid treated clay, and said alkaline reagent comprises soda lime.

ROBERT P. FERGUSON.
